DESIGN FOR A COMBINATION SUNDIAL AND BIRDBATH

George E. Vinnedge, Fort Worth, Tex.

Application June 17, 1946, Serial No. 130,820

Term of patent 7 years

(Cl. D42—7)

To all whom it may concern:

Be it known that I, George E. Vinnedge, a citizen of the United States, residing in Fort Worth 7, in the county of Tarrant and State of Texas, have invented a new, original, and ornamental Design for Combination Sundials and Birdbaths, of which the following is a specification, reference being had to the accompanying drawing, forming a part thereof.

The figure is a perspective view of a combined sundial and birdbath, showing my new design.

I claim:

The ornamental design for a combined sundial and birdbath, substantially as shown.

GEORGE E. VINNEDGE.
